UNITED STATES PATENT OFFICE

111,600

DESIGN FOR AN ELECTRIC SADIRON

David Goldberg, Great Neck, N. Y.

Application April 29, 1937, Serial No. 69,044

Term of patent 7 years

To all whom it may concern:

Be it known that I, David Goldberg, a citizen of the United States, residing at G1, Norfolk Road, Great Neck, Long Island, in the county of Nassau and State of New York, have invented a new, original, and ornamental Design for an Electric Sadiron, of which the following is a specification, reference being had to the accompanying drawing, forming part thereof.

Fig. 1 is a view in side elevation of an electric sadiron showing my new design;

Fig. 2 is a top plan view of the sadiron shown in Fig. 1;

Fig. 3 is a view in front elevation of the same; Fig. 4 is a view in rear elevation of the same.

I claim:

The ornamental design for an electric sadiron substantially as shown.

DAVID GOLDBERG.
